UNITED STATES PATENT OFFICE.

SEBASTIAN ZIANI DE FERRANTI, OF HAMPSTEAD, LONDON, ENGLAND.

ELASTIC-FLUID TURBINE-ENGINE.

No. 872,806.

Specification of Letters Patent.

Patented Dec. 3, 1907.

Application filed June 9, 1904. Serial No. 211,838.

To all whom it may concern:

Be it known that I, SEBASTIAN ZIANI DE FERRANTI, a subject of the King of Great Britain and Ireland, and residing at 31 5 Lyndhurst road, Hampstead, London N.W., England, have invented certain new and useful Improvements Relating to Elastic-Fluid Turbine-Engines, of which the following is a specification.

10 My invention relates to elastic fluid turbine heat engines. In such heat engines when considering the expansion alone, it is important for high efficiency to work with the highest possible upper limit of temperature 15 of the working fluid and the practicable limit is soon reached owing to the fact that the materials of construction, of which superheaters and other such appliances are made, cannot stand satisfactorily temperatures higher than, say, 400° C., with the high 20 pressure of, say 300 lbs., or 400 lbs., per square inch (necessary for efficient utilization) where the heat has to be transmitted to the working fluid through them. On the 25 other hand, in such turbine heat engines considering the obtaining of the pressure of the working fluid, it is largely impracticable to employ a non-condensable elastic fluid as the working fluid (1) because of the complexity, 30 bulk and expense of the separate high pressure compressing plant and (2) because the efficiency of compression in such plant is comparatively low, so that the advantages of using a high temperature in the expansion 35 would be canceled by the loss in compression. Now, the object of my invention is to overcome these difficulties, so as to render possible the obtaining efficiently of a large body of elastic fluid at a high temperature 40 and pressure and the efficient utilization of the energy of that elastic fluid in a turbine engine.

The first part of my invention consists broadly in employing condensable elastic fluid as the bulk of the working fluid, superheating that fluid internally by means of liquid or gaseous fuel or solid fuel in a finely divided state, together with the necessary air supplied for combustion under the maximum pressure of the cycle, the utilizing the working fluid by expansion in a fixed part of the turbine, whereby its pressure is converted into velocity, its kinetic energy being then extracted by a multiple impact re-action turbine.

The second part of my invention consists in employing (in conjunction with a turbine as described under the first part of my invention) the exhaust from the turbine to heat the feed fluid or to superheat vapor or to heat air, so that an efficient heat engine is obtained while working non-condensing or with atmospheric pressure condensing.

The third part of my invention consists in employing the exhaust from a turbine according to the first part of my invention to evaporate separately a second fluid, which is utilized in a second turbine, the exhaust from which passes to a condenser.

The second turbine mentioned in the preceding paragraph may be an isothermal turbine.

My invention further consists in the apparatus hereinafter described.

It will be seen from the following description that the improved turbine is essentially a steam turbine (taking steam as an example of a condensable elastic fluid), the gaseous products of combustion amounting at most to only one third of the total working fluid; in this respect the invention differs materially from the many essentially gas turbines, in connection with which suggestions have been made to add a relatively small quantity of water or steam with a view to reducing the temperature of the hot gases.

With the above cycles involving high temperature fluid completely expanded to practically atmospheric pressure in the fixed parts of the turbine before passing to the multiple impact wheels it is possible to maintain the fluid practically dry during the process of extracting its kinetic energy without requiring stage reheating.

Referring to the accompanying drawings:— Figures 1 and 2 show respectively sectional plan and elevation of one form of internal combustion superheating chamber, together with part of a coöperating turbine, Fig. 3 being a modification in which multiple nozzles are used; Fig. 4 shows a general arrangement of apparatus in which a non-condensing turbine is used in conjunction with a regenerator, Fig. 5 being a modification in which the exhaust from a primary turbine evaporates fluid for use in a secondary condensing turbine; Fig. 6 shows a further modification in which the secondary turbine is of the isothermal type, while Fig. 7 shows a general arrangement of apparatus in which

the whole of the energy of the working fluid is derived primarily from the internal combustion chamber.

All the drawings are of a diagrammatic nature, the piping, for example, being in many instances represented by single lines; where desirable, similar parts of the apparatus in the different figures are denoted by the same reference symbols.

- 10 In carrying my invention into effect according to one form employing steam as the bulk of the working fluid, I provide any suitable form of steam boiler or generator, *a*, (see Fig. 4) and I preferably superheat the steam 15 in an external superheater, *b*, before passing it to one or more internal superheating chambers, *c*. A detail view of one form of such a chamber is shown in Figs. 1 and 2; according to this form, it consists of a cylindrical vessel, 20 *d*, one end of which communicates with a fixed nozzle, *e*, of the turbine. This nozzle is so proportioned as regards cross sectional area throughout its length as to provide for the complete expansion of the gases down to 25 the atmosphere. The whole of the energy of the working fluid being converted into velocity in the fixed nozzles, multiple impact reaction turbine wheels are employed for the extraction of the energy and these are made 30 of sufficient diameter to reduce the velocity of the rotating shaft to any required extent, the circumferential velocity being kept sufficiently low by multiplying the number of stages in which the extraction of the velocity 35 is effected. A combustion tube or chamber, *f*, is provided within the end of the internal superheating chamber, *d*, remote from the nozzle and is preferably concentric with the chamber itself. To this chamber, *f*, compressed air is supplied from the compressor, 40 *n*, (see Figs. 4, 5 and 6) by way of the pipe, *h*, and by another pipe, *i* liquid or gaseous fuel or solid fuel in a finely divided state is admitted. The compressed air supply may be 45 arranged to carry in the fuel supply in any suitable and well known manner. The superheated steam from the external superheater, *b*, passes by way of the pipe, *k*, to the nozzle end of a space, *l*, surrounding the nozzle, *e*, for any desired proportion of its length 50 and also surrounding the chamber, *d*, and passes along this space thus exerting a cooling effect to the end remote from the nozzle, where it passes within the chamber, *d*, by 55 way of holes, such as *m*. The chamber, *f*, is preferably lined or partly filled with refractory material to insure continued ignition, once this has been started. Any suitable form of igniter may be employed for effecting 60 the ignition of the combustible when starting. Instead of superheated steam, feed water may be circulated in the space, *l*, but the arrangement is less efficient from the thermodynamic point of view.

65 According to a modified form, the jacket,

l, may be dispensed with and the chamber, *d*, and nozzle, *e*, lined over a portion or the whole of their combined surfaces with a suitable fire resisting material, the metal shell in this way not being directly exposed to the hot gases; in this case, the superheated steam is led directly to the end of the chamber, *d*, remote from the nozzle, *e*, the holes, *m*, being of course, dispensed with.

It will be obvious that if desirable a combination of the two systems of jacketing and lining with refractory material may be adopted.

In the operation of the apparatus, compressed air and fuel are supplied to the combustion chamber and ignited starting a flame therein. Superheated steam is then admitted into the internal superheater chamber and flows to the nozzle, being mixed with the flame, the temperature of the whole being thereby raised to, say 800° C., assuming the compressed air to be supplied at something like 300 lbs., per square inch; the working fluid, consisting of steam and the products of combustion, issues through the nozzles, 80 having its heat energy converted into velocity and dropping in temperature to something like 300° C. before reaching the blades of the multiple impact reaction turbine. Part of this turbine is indicated in section in 85 Figs. 1 and 2, the moving and stationary blades being shown respectively at *o* and *r*. The total useful velocity of the working fluid may be taken out with, say, something like 90 six reactions and at a workable rim speed of 95 the turbine wheel.

Another modification of the internal superheater is shown in Fig. 3, the arrangement being the same generally as that already described with reference to Figs. 1 and 2 but instead of one expanding nozzle, *e*, two or more such nozzles are arranged all issuing directly from the combustion chamber, *d*.

If the turbine is to be worked without a condenser, then the exhaust from the turbine 110 is utilized either to superheat the steam or to heat the feed water (sufficiently, it may be, to partially vaporize it) or to heat the compressed air for combustion or for any combination of these uses, so that its heat energy 115 may be extracted as fully as possible. In the example shown in Fig. 4, the turbine, *s*, is represented as coupled to a dynamo, *t*, the boiler feed entering by the pipe, *u*, and being preferably sprayed into the turbine exhaust, 120 *v*, whence it passes by way of the pipe, *w*, to a hot well or reservoir *x*. A pump *z*, drawing from this hot well serves to feed the boiler, the feed water passing through the pipe, *2*, to the regenerator, *3*, situated in the turbine exhaust and thence through the pipe, *5*, economizer, *6*, and pipe, *7*, to the generator, *a*. I prefer, however, to pass the exhaust from the primary turbine, *s*, as shown in Fig. 5, into 125 an evaporator, *8*, where a second fluid, say 130

water, is evaporated at about atmospheric pressure. The non-condensable gases of the primary exhaust discharge by way of the pipe, 9, while the steam generated passes through a pipe, 10, to a secondary turbine, 11, which may or may not be on the same spindle as the first. The exhaust from the secondary turbine, 11, passes to a condenser, 12, represented as of the jet type and provided with the usual air pump, 13. A pump arranged conveniently with two water cylinders, 14 and 15, serves on the one hand to feed the evaporator, 8, through the pipe, 16, and on the other hand to draw the condensed exhaust from the primary turbine from the evaporator through the pipe, 17, and return it by way of the economizer, 6, to the generator, a.

The secondary turbine, 11, is preferably an isothermal expansion turbine as described in my prior application, No. 179407, with fire superheating between the stages, but any form of turbine may be used for the second stage with varying economy, according to the merit of the particular type adopted.

Referring to Fig. 6, a general arrangement is shown, in which an isothermal expansion turbine of the type above referred to is used as the secondary turbine. It will be seen that the hot gases from the furnace, 18, pass to the chimney, 19, through a flue in which tube elements are arranged constituting the feed-water heater, or economizer, 6, boiler proper, 20, reheaters, 21, and superheaters, 22 and 23. The feed pumps, 14 and 15, and the air compressor, n, are indicated as driven by worm gearing, 25, from the main turbine shaft but any other convenient drive may be adopted.

Starting from the main boiler feed pump, 15, the condensed exhaust from the primary turbine, s, is drawn from the evaporator 8, through the pipe, 17, and passes thence the pipe, 5, to the economizer, 6, and boiler 20. The steam generated in the boiler passes to the superheater elements 22, and through the pipe, 27, to the internal superheating chamber, c. Compressed air is supplied to this chamber from the air compressor, n, by way of the pipe, h, the supply of fuel being as shown in the detail Figs. 1 and 2. After expanding in the nozzle, e, the fluid does work in the primary turbine, s, exhausting thence by way of the pipe, 28, to the evaporator, 8, where it partially condenses. The heat thereby given up serves to evaporate the water drawn from the hot-well, x, of the secondary turbine, 11, by way of the pipe, 29, and fed into the evaporator by the feed pump, 14, through the pipe, 16, the steam generated passing by way of the pipe, 30, to the superheater, 23, and thence to the secondary turbine, 11. After a partial expansion in the turbine, the steam returns to the flue through the pipe, 31, and is re-super-

heated in the reheater, 21, before returning to the turbine for a further expansion. Only one reheater is shown in the drawing but several are preferably used as fully described in my previous patent above referred to. Finally, the steam exhausts to a condenser, 12, into which cold water is injected by way of the pipe u; an air pump and hot-well are indicated at 13 and x respectively. The primary and secondary turbines are shown as in a previous modification coupled together and driving the dynamo, t. A regenerator may be arranged, if desired, in the exhaust of the secondary turbine.

In all the above forms of my invention the bulk of the working fluid is a condensable elastic fluid such as steam generated in a separate steam generator. In such cases the air compressor need only absorb about 15% of the useful power generated but I find that if the turbine be used non-condensing, i. e., non-vacuum-condensing, or atmospheric pressure condensing, and a regenerator be employed to heat and partially evaporate the feed water it is quite practicable to complete the required evaporation by internal combustion so that the separate steam generator can be omitted. Even in such a case however the quantity of products of combustion will not amount to more than one-third of the total working fluid. The work done in the air compressor, in the latter case, becomes a greater proportion of the useful work and may be as much as 50%. In order to attain economy, in a commercially practicable apparatus, it is necessary, therefore, that this compression should be effected efficiently and that the compressor should not be too large and costly, as it tends to become in large plants.

An example of a general arrangement of apparatus suitable for carrying into effect the cycle just indicated is shown in Fig. 7, the same reference symbols being used for the most part as in previous modifications.

The exhaust from the turbine, s, passes by way of the pipe, 28, to the evaporator, 8, which in this case serves as a regenerator, the condensed portion of the exhaust being drawn off through the pipe, 32, by the feed pump, 33, which forces it back through the regenerator by way of the pipe, 34, make up feed being introduced through the pipe, u. The regenerator heats all the water to the boiling point and may evaporate a certain proportion of it under pressure. This proportion may amount to one third of the whole. Passing on through the pipe, 35, the resulting mixture of steam and water enters the internal combustion chambers, c, where the remaining two-thirds (for example) is evaporated and the whole superheated to the required extent. The remaining steps of the cycle, viz., expansion in the nozzles, e, and extraction of the resulting

velocity in the multiple impact reaction turbine, *s*, have already been described with reference to previous modifications.

The air compressor may be of any suitable type; in the figures the compression is indicated as being effected in stages and although not shown in the drawings, coolers may be used in conjunction with such stage compression in order to render the process on the whole substantially isothermal.

Having now described my invention, what I claim as new and desire to secure by Letters Patent is:—

1. In a turbine installation, the combination of a source of condensable elastic fluid under pressure; a combustion chamber connected to said source; means other than said combustion chamber for heating said source; means for introducing into said chamber fuel and oxidizing means, the combustion of said fuel acting to superheat said fluid to a high temperature; one or more de Laval type nozzles issuing from said chamber and proportioned to expand said fluid to exhaust pressure in a single stage together with a multiple impact turbine receiving the fluid from said nozzle or nozzles.

2. In a turbine installation, the combination of a source of condensable elastic fluid under pressure; a combustion chamber connected to said source; means for introducing into said chamber fuel and oxidizing means; the combustion of said fuel acting to superheat said fluid to a high temperature; one or more de Laval type nozzles issuing from said chamber and proportioned to expand said fluid to exhaust pressure in a single stage together with a multiple impact turbine receiving the fluid from said nozzle and means for utilizing heat in the exhaust therefrom, exhaust heat acting to assist in the production of said elastic fluid.

3. In a turbine installation, the combination with a source of supply of condensable elastic fluid of an internal combustion superheater connected to said source of supply; means other than said combustion chamber for heating said source; a multiple impact turbine and one or more single stage expansion nozzles interposed between the superheater and turbine.

4. In a turbine installation, the combination with a source of supply of condensable elastic fluid of an internal combustion superheater arranged to receive the condensable fluid therefrom, means other than said combustion chamber for heating said source, a multiple impact turbine and one or more single stage expansion nozzles interposed between the superheater and turbine together with means for utilizing heat in the exhaust from said turbine, substantially as described.

5. In a turbine installation, the combination of a boiler; an external superheater connected therewith; an internal combustion

superheater connected with said external superheater; one or more expansion nozzles connected with said internal combustion superheater and a multiple impact turbine receiving the fluid from said nozzles.

6. In a turbine installation, the combination of a steam boiler; an external superheater connected therewith; an internal combustion superheater connected with said external superheater; one or more single stage expansion nozzles receiving the fluid from said combustion superheater; a multiple impact turbine coöperating with said nozzles and means for utilizing heat energy in the exhaust of said turbine.

7. In a turbine installation, the combination with a source of condensable fluid under pressure of an independent internal combustion superheating chamber connected therewith; a flame chamber disposed within said combustion chamber; means for introducing into said flame chamber oxidizing means at the maximum pressure of the cycle and a fuel supply to said flame chamber.

8. In a turbine installation using condensable elastic fluid as the bulk of the working fluid, the combination with a source of condensable fluid under pressure of an independent internal combustion superheating chamber connected therewith; a flame chamber disposed within said combustion chamber; means for introducing into said flame chamber oxidizing means at the maximum pressure of the cycle; a fuel supply to said flame chamber; a multiple turbine and one or more single stage expansion nozzles interposed between the superheater and the turbine.

9. In a turbine installation, the combination of a combustion chamber and a source of heat therefor; means for introducing into said chamber the constituent elements from which the working medium is formed, the bulk of said working medium consisting of condensable elastic fluid; a vessel or chamber other than said combustion chamber in which an ultimate constituent of said working medium receives heat from a second source; a de Laval type nozzle issuing from said combustion chamber and a turbine receiving the fluid from said nozzle.

10. In a turbine installation, the combination with a source of supply of condensable elastic fluid of an internal combustion superheater arranged to receive the condensable fluid therefrom; a multiple impact primary turbine and one or more single stage expansion nozzles interposed between the superheater and turbine together with a secondary turbine and means for evaporating the working fluid of said secondary turbine by the exhaust heat of said primary turbine.

11. In a turbine installation, the combination with a source of supply of condensable elastic fluid of an internal combustion super-

heater arranged to receive the condensable fluid therefrom, a multiple impact turbine and one or more single stage expansion nozzles issuing directly from said chamber together with jacket means for cooling said nozzles.

12. In a turbine installation, the combination of a plurality of connected chambers; a source of heat for a fluid contained in one 10 of said chambers said fluid receiving heat from said source by transmission through the containing envelop thereof and means for imparting a balance of heat to said fluid by admixture with a comparatively small 15 bulk of a heating medium receiving heat from a second source in another of said chambers; nozzle means connected to the second mentioned of said chambers and a turbine receiving the fluid from said nozzle.
13. In combination, means for mixing condensable elastic fluid with a relatively small bulk of the products of an exothermic chemical reaction to superheat said condensable fluid; means for giving velocity to said working fluid so produced; rotary motor means 25 impinged on by said fluid together with means including an evaporator for utilizing

heat contained in the exhaust of said rotary means.

14. In combination, means for producing 30 superheated condensable elastic fluid, said means including an independent boiler; an internal combustion superheater connected to said fluid producing means; means for giving velocity to the working fluid issuing 35 from said internal combustion superheater together with rotary motor means impinged on by said fluid.

15. In combination, means for generating 40 condensable elastic fluid; means for admixing with said fluid a certain bulk of the products of an exothermic chemical reaction to highly heat said fluid, said admixing means including a vessel or chamber separate from said generating means; means for giving 45 velocity to the working fluid produced by such admixture and rotary means impinged on by said fluid.

In witness whereof I have hereunto set my hand in presence of two witnesses.

SEBASTIAN ZIANI DE FERRANTI.
